UNITED STATES PATENT OFFICE.

ROBERT H. READ, OF SCHENECTADY, NEW YORK, ASSIGNOR TO GENERAL ELECTRIC COMPANY, A CORPORATION OF NEW YORK.

GLOBE-HOLDER FOR ARC-LAMPS.

SPECIFICATION forming part of Letters Patent No. 733,596, dated July 14, 1903.

Application filed April 3, 1901. Serial No. 54,123. (No model.)

To all whom it may concern:

Be it known that I, ROBERT H. READ, a citizen of the United States, residing at Schenectady, county of Schenectady, State of New York, have invented certain new and useful Improvements in Globe-Holders for Arc-Lamps, of which the following is a specification.

The object of this invention is to provide a simple and effective device for clamping the inner globes of arc-lamps. Considerable difficulty is experienced in practice from the breaking of the globes by reason of the pressure of the clamping devices which secure the bottom of the globe to its support, mounted on the yoke of an arc-lamp. The device must maintain a firm grip on the globe, so as to make substantially an air-tight joint between its support and the globe-bottom, and yet must be sufficiently yielding to prevent breaking of the globe from contraction and expansion when the lamp is idle or operating. A rigid clamp has been found ineffective by reason of its unyielding characteristics and inability to permit the necessary expansion and contraction. I provide a globe-holder by which a number of elastically - yielding clamp-jaws are supported from the stem of the globe-holder, which are adapted to slide in grooves formed in a horizontal rotatory disk mounted on the stem of the holder, the grooves or slots curving toward the axis of the globe, so that when the disk is rotated the clamp-jaws will be shifted to or from the axis of the globe, so as to grip or release it.

The novel features of the invention will be more specifically described hereinafter and will be definitely indicated in the appended claims.

In the accompanying drawings, which illustrate the invention, Figure 1 is an elevation, partly in section, of a globe-holder embodying the improvements. Fig. 2 is a detail of the blank from which the clamp-jaws are formed. Fig. 3 is a detail view showing the curved shape of the spring-clamp. Fig. 4 is the rotatory disk which controls the adjustment of the clamp-jaws.

1 represents a globe-holder adapted to be fastened to the yoke of an arc-lamp in the ordinary manner, carrying a stem on the top

of which is a recessed seat 2 for the bottom of an inner globe, (shown at 3.) It is usual to provide a soft lining for the bottom of this seat of asbestos, as indicated in the drawings, 55 thereby cushioning the globe and promoting the tightness of the seal. On the stem of the support I mount a clamp made of sheet metal, as thin steel or phosphor-bronze, and provided with a plurality of vertical curved jaws or 60 fingers 4 4^a. The clamp is made from a blank of sheet metal of substantially the shape indicated in Fig. 2, the clamp-jaws being curled in some such way as indicated in Fig. 3, and the supporting-web being curved to hug the 65 stem of the globe-support and provided with two projecting ears, as indicated in Fig. 1, which are perforated, as indicated at 5 5^a, to take a set-screw. The globe-seat is removably secured to the stem of the support, being connected thereto by a screw connection, as indicated in Fig. 1, and below the threaded joint is a shoulder on which is seated, sufficiently loosely to permit its being revolved by the fingers, the regulating-disk 6. The disk may 70 have a milled edge or be otherwise shaped to permit easy turning. It is provided with a number of slots extending from the periphery inward, as indicated at 7 7^a in Fig. 4, into which the spring-jaws may be guided. The 75 inner extremity of the grooves may have an offset, as indicated at 8, to lock the jaws in clamping position when set. By turning the disk through a small angle the jaws may be shifted into clamping position or releasing position with relation to the globe, and the latter is firmly anchored in its seat by an elastic grip.

What I claim as new, and desire to secure by Letters Patent of the United States, is— 90

1. A globe-holder for an arc-lamp, comprising a plurality of elastic clamp-jaws extending above the plane of the globe-seat, a rotatable device having guides parallel to the plane of the seat and engaging the clamp-jaws along lines extending outward from the globe-axis, said rotatable device being arranged to prevent the jaws jarring loose after the globe has been secured. 95

2. A globe-holder for an arc-lamp, comprising a plurality of spring-jaws mounted on the globe-support and extending above the globe- 100

seat, a rotatable disk having a guide-slot for each jaw to shift it into and out of engagement with the neck of the globe, said disk being arranged to prevent the jaws jarring loose after the globe has been secured.

3. A globe-holder for an arc-lamp, comprising a globe-seat, a plurality of spring-jaws rigidly attached to the support and extending above the seat, and a slotted clamp-disk engaging the jaws rotatably mounted on the support.

4. A globe-holder for an arc-lamp, comprising a plurality of elastic clamp-jaws formed from a strip of sheet metal having a web bent around the globe-support and secured in place, and a slotted disk shifting the jaws to and from the axis of the globe.

15 In witness whereof I have hereunto set my hand this 30th day of March, 1901.
